UNITED STATES PATENT OFFICE.

FRANK L. NICHOLS, OF WASHINGTON, DISTRICT OF COLUMBIA, ASSIGNOR
TO ELK MANUFACTURING AND VENDING COMPANY, OF WASHINGTON,
DISTRICT OF COLUMBIA, A CORPORATION OF DELAWARE.

DESIGN FOR A CASING FOR VENDING-MACHINES.

SPECIFICATION forming part of Design No. 36,786, dated February 9, 1904.

Application filed January 19, 1904. Serial No. 189,762. Term of patent 3½ years.

To all whom it may concern:

Be it known that I, FRANK L. NICHOLS, a citizen of the United States, residing at 815 G street northwest, in the city of Washington, in the District of Columbia, have invented a new, original, and ornamental Design for a Casing for Vending-Machines, of which the following is a specification, reference being had to the accompanying drawing, forming a part thereof.

The figure is a perspective view of a casing

for a vending-machine, showing my new design.

What I now claim as new, and desire to secure by Letters Patent, is—

The ornamental design for a casing for a vending-machine as herein shown.

FRANK L. NICHOLS.
